[57] CLAIM

I claim the ornamental design for a foot massager, as shown and described.

DESCRIPTION

FIG. 1 is a perspective view of a massager, showing our new design;

FIG. 2 is a front elevational view thereof, the rear elevational view, the top plan view and bottom plan view being identical thereto; and,

FIG. 3 is a left side elevational view thereof, the right side elevational view being identical thereto.
